No. 696,803.

Patented Apr. 1, 1902.

W. S. DE CAMP.

ANGLE COCK ADJUSTER FOR AIR BRAKES.

(Application filed Dec. 31, 1901.)

(No Model.)

UNITED STATES PATENT OFFICE.

WILLIAM S. DE CAMP, OF CHILLICOTHE, OHIO.

ANGLE-COCK ADJUSTER FOR AIR-BRAKES.

SPECIFICATION forming part of Letters Patent No. 696,803, dated April 1, 1902.

Application filed December 31, 1901. Serial No. 87,885. (No model.)

To all whom it may concern:

Be it known that I, WILLIAM S. DE CAMP, of Chillicothe, in the county of Ross and State of Ohio, have invented a new and useful Improvement in Angle-Cock Adjusters for Air-Brakes, of which the following is a specification.

My invention relates to certain improvements upon the angle-cock adjuster for air-brakes described and claimed in my prior United States patent, No. 688,602, December 10, 1901. In describing that invention it is necessary to state in a preliminary way that in the ordinary air-brake system a train-pipe runs from end to end of the car and terminates at each end in an angle-cock the mouth of whose casing dips down at an angle to join onto the flexible hose that connects the train-pipe between the cars. Through this train-pipe, its hose-couplings, and angle-cocks the air passes from the locomotive to operate the brakes, which, as usual, are put into action by a reduction of pressure. In coupling up the cars the angle-cocks are ordinarily operated by hand through a handle by the brakeman in order to give free passage of air through the train. This act is one that is dependent upon the memory of the brakeman, and if he should forget to so "cut in" the angle-cocks, and thus preclude continuity in the air-passage through the train-pipe, all the air-brakes in the rear of this closed angle-cock are inoperative and useless, and serious danger and delay may arise therefrom.

The object of my present invention is, as in my patented device, to provide a means whereby the engineer may from his locomotive adjust any or all the angle-cocks to the open or cut-in position in case of such oversight; and to that end it consists in a new and useful construction and arrangement of a pneumatic angle-cock adjuster designed to be operated by an increase of air-pressure in the train-pipe over and above a normal pressure of sixty-five pounds. This new construction secures certain advantages over and overcomes certain difficulties incident to the construction heretofore patented by me, as will be hereinafter described.

Figure 1 is a plan view, partly in section, of my angle-cock adjuster applied to the train-pipe. Figs. 2 and 3 are enlarged sectional de-

tails, Fig. 2 being on line 2 2 of Fig. 1 and Fig. 3 on line 3 3 of Fig. 1; and Fig. 4 is a side view of the parts shown in Fig. 1.

55

In the drawings, A A' represent the train-pipe, which runs from end to end of the car and at each end has the ordinary angle-cock B, which in my present invention comprehends a special form of casing with one of its mouths connecting with the section A' of the train-pipe and its other mouth turned down at an angle to connect with the flexible hose C, that connects the train-pipe between cars. In this casing is arranged the usual turning 60 plug C', having a transverse passage-way c through it, with a crank-handle C² on the end of the same outside the case. This crank-handle is turned ordinarily by hand, and when turned into a position in the plane of the train-pipe the passage-way c in its plug opens communication between the train-pipe and the flexible hose, and when said crank-handle is turned to a position at right angles to the train-pipe communication in the latter is cut off. 70 75

My invention provides means for adjusting the angle-cock plug to the open position in a pneumatic manner by the engineer from the locomotive at will, but by a different means from that shown in my previous patent. 80

The train-pipe, near each end of the car, is cut in two to form the two sections A A', and between them is fitted a tubular coupling d, whose ends are screw-threaded to receive the screw-threaded ends of the train-pipe sections 85 A A', by which it is supported and which thus forms a continuation of the train-pipe. Cast in one piece with this coupling d is a cylinder D of about three inches internal diameter, one end of which is cast with a closed 90 head D', and the other end is formed with a flange d' and a detachable head D², bolted or otherwise secured to said flange. Within this cylinder there is arranged a piston E, whose sliding surfaces are packed air-tight. 95 A sleeve E' is secured centrally to piston and extends through an opening f in one head of the cylinder, and in its outer end is loosely seated a rod E², jointed to an arm g on the crank-handle C² of the angle-cock plug, so that 100 when the piston moves outwardly or toward the cast head of the cylinder this sleeve E' and rod E² will force the crank-handle of the angle-cock plug to the cut-in position, or the position

in which the passage-way in the plug opens a continuous communication through the train-pipe. To give the necessary movement to the piston to produce this result, I employ 5 a valve F, which opens at a predetermined pressure and allows air to pass to the air-tight side of the cylinder. This valve (see Fig. 2) is intended to take air from the train-pipe, and at a predetermined pressure in excess of 10 the ordinary train-pressure to open the train-pipe into the cylinder to actuate the piston. This valve F is mounted on a seat 1 at an intermediate point between the cylinder D and coupling d. This seat is also cast in one piece 15 with said coupling and cylinder and has a port 2, Figs. 1 and 3, leading from the center of the valve-seat to the interior of the cylinder D, and another port 3, leading from the interior of the coupling and the main train-pipe 20 to the valve-seat.

Within the seat 1 there is held a conical point 4, mounted upon a metal diaphragm 5, which point enters and opens or closes the hole 2, according to the pressure of air coming in from the inlet-port 3. The diaphragm is clamped in the cup by a washer 6 and an external casing 7, which is flanged and screw-threaded, so as to be turned into the cup 1. A helical spring 8 is contained in the case 7 30 and is seated at one end upon a center-pin 9 on a lug attached to the diaphragm and at the other end is held by an adjustable plug 10, which is screwed into the top of the case and may be turned in or out to vary the tension 35 of the spring. An external cap 11 incloses this plug and screws onto the threads of the plug, so as to protect the same and complete the inclosure of the case. This form of pressure-valve is not new in itself, but is a 40 convenient and practical form of valve for admitting air to the cylinder only when the air-pressure exceeds the tension of the spring.

Now if by accident or forgetfulness an angle-cock is left closed at any point on the 45 train and the engineer desires to open it pneumatically he simply throws a greater air-pressure on the train-pipe than the normal, and this excess of air-pressure will open valve F and allow air to pass from the train-pipe to 50 the cylinder D and there acting upon the piston forces it back and turns the angle-cock plug. This is easily and certainly accomplished, for the reason that the conical point 4 of valve F is held closed on port 2 by spring 55 9 at the ordinary pressure of sixty-five pounds and only opens the port 2 by an excess of this normal air-pressure acting against the diaphragm 5.

I will now explain how the air-pressure gets 60 past a closed angle-cock that may be between the adjuster-cylinder and the engine. For this purpose each angle-cock is formed with a special casing (see Figs. 1 and 4) in which is cast a valve-chamber 12, containing a 65 spring-valve 13. This valve-chamber has one port 14 leading to one side of the angle-cock plug C' and another port 15 leading to the

other side of said plug. The valve 13 seats itself toward the port 14 from the tension of the spring 16 and is retained in its bored 70 chamber by a removable screw-plug 17. This valve 13 has a very light spring, that always allows the air-pressure to force it back and the air to pass by it and through the port 15 to the other side of the angle-cock; but this 75 valve acts as a check-valve for any movement of the air in the opposite direction, so that if this angle-cock is at the rear end of the train it closes automatically and does not allow air to waste out of the train-pipe. This 80 valve may be vertical. Where the piston-sleeve E passes through the end of the cylinder there is a leather head w, forming an elastic pad which fills the end of the cylinder and fits closely down to the said sleeve and acts 85 like a stuffing-box in connection with a circular ridge w' of the piston, which when the piston reaches the end of its stroke presses tightly against the leather head and forms a tight joint to prevent the escape of air. By 90 providing this sleeve and allowing it to work in true axial line through the end of the cylinder I get at this point not only a species of stuffing-box, but the connection between the rod E² and the sleeve is a loose one, that allows some lateral play at this point, that prevents cramping and binding of the plug-arm rod.

In the side of the cylinder D there is tapped a waste-cock w², which when opened allows 100 the air in the cylinder to escape, so that the piston can easily be moved back again when it is desired to turn by hand the angle-cock handle back to a closed position. When the air escapes through this waste-cock, the dia- 105 phragm-valve closes automatically.

At the rear end of a train having my invention the train-pipe must be provided with a "back-up hose" or dummy coupling, which permanently holds that end of the train-pipe 110 closed.

It will be understood that the normal train-pipe pressure is not to be limited to sixty-five pounds, but may be less for low-speed brakes and higher for high-speed brakes—i. e., it 115 may be maintained at any arbitrary pressure.

In making use of my invention it is not only to be applied to the air-brake pipe of a train, but is equally applicable to the air-whistle pipe of modern passenger-trains, 120 which have the same hose connections and angle-cocks between the cars and are used for the transmission of signals between the conductor and the engineer.

In pointing out the advantages of my present improvement over the devices contained 125 in my previous patent I would state that my present construction is not only much simpler, but it entirely dispenses with the outside or supplemental air-pipes and the double valves of that construction. These outside air-pipes are liable to be struck and de-ranged on the road, and if rendered leaky they would allow the air to escape and pro- 130

duce an involuntary and possibly dangerous application of brakes, which might permanently disable the train.

By the term "angle-cock" as used by me I mean any cock that couples the train-pipe to the flexible hose between cars, whether said cock-casing be bent at an angle or straight.

Having thus described my invention, what I claim as new, and desire to secure by Letters Patent, is—

1. An angle-cock adjuster comprising pneumatic means for turning the plug of said cock, and a by-pass valve for carrying the air around the angle-cock plug, said by-pass valve being located in the casing of the angle-cock substantially as described.

2. A pneumatic angle-cock adjuster comprising a cylinder a pressure-valve and a piston for turning the angle-cock by increased air-pressure, and a by-pass valve located in the angle-cock casing to pass air around the plug of the angle-cock substantially as described.

3. The combination with the train-pipe and the angle-cock controlling the same; of a cylinder, a coupling for the train-pipe and a valve-seat, all cast in one piece, and a pressure-valve adapted to open into the cylinder at a predetermined pressure substantially as and for the purpose described.

4. An angle-cock having a turning plug with an arm attached thereto and a pneumatic piston and cylinder for working said arm, a valve-chamber opening on opposite

sides of the turning plug, and a valve located 35 in said chamber and controlling the passage of air around the plug substantially as and for the purpose described.

5. An angle-cock having a turning plug with an arm attached thereto and a pneumatic piston and cylinder for working said arm, a valve-chamber opening on opposite 40 sides of the turning plug, a valve located in said chamber and controlling one of said openings, a spring arranged behind the valve, 45 and a removable cap closing the end of said valve-chamber substantially as described.

6. In an angle-cock adjuster, the combination with the plug-arm and its turning-rod; of a pneumatic cylinder and piston for operating the rod, said piston having a hollow tube or sleeve extending through the end of the cylinder and loosely receiving and acting upon the rod which turns the cock-plug substantially as described.

7. In an angle-cock adjuster, the combination with the plug-arm and its turning-rod; of a pneumatic cylinder having an elastic cushion in its end, a piston having a tubular sleeve extending through and closely fitting 50 said cushion and having also a ring or concentric flange about the sleeve adapted to pinch the cushion at the end of the stroke, substantially as described.
